UNITED STATES PATENT OFFICE.

CHARLES P. RANDOLPH, OF OAK PARK, ILLINOIS, ASSIGNOR TO EDISON ELECTRIC APPLIANCE COMPANY, INCORPORATED, OF CHICAGO, ILLINOIS, A CORPORATION OF NEW YORK.

DESIGN FOR A WAFFLE IRON.

Application filed December 13, 1926. Serial No. 20,035. Term of patent 14 years.

To all whom it may concern:

Be it known that I, CHARLES P. RANDOLPH, a citizen of the United States, residing at Oak Park, in the county of Cook, State of Illinois, have invented a new, original, and ornamental Design for Waffle Irons, of which the following is a specification, reference being had to the accompanying drawing, forming a part thereof.

The single figure of the drawing is a perspective view of a waffle iron embodying my new design.

I claim:

The ornamental design for a waffle iron substantially as shown.

In witness whereof, I have hereunto set my hand this 7th day of December, 1926.

CHARLES P. RANDOLPH.
